(57) **CLAIM**

The ornamental design for a display screen with animated graphical user interface as shown and described.

DESCRIPTION

The patent or application file contains at least one drawing executed in color. Copies of this patent with color drawing(s) will be provided by the Office upon request and payment of the necessary fee.

This application is related to the following commonly owned co-pending patent applications: U.S. application Ser. No. 29/809,656, entitled "Display Screen With Animated Graphical User Interface"; and U.S. application Ser. No. 17/483,278, entitled "Independently Randomly Accumulated Awards Associated With Respective Sets of Symbol Display Positions".

FIG. 1 is a front view of a first image in a sequence for a display screen with animated graphical user interface of our new design.

FIG. 2 is a front view of a second image thereof.

FIG. 3 is a front view of a third image thereof.

FIG. 4 is a front view of a fourth image thereof.

FIG. 5 is a front view of a fifth image thereof.

FIG. 6 is a front view of a sixth image thereof; and,
FIG. 7 is a front view of a seventh image thereof.

The broken lines in the drawings show the display screen which forms no part of the claimed design.

The appearance of the transitional image sequentially transitions between the images shown in FIGS. 1-7. The process or period in which one image transitions to another image forms no part of the claimed design.
